UNITED STATES PATENT OFFICE.

GOODWIN B. SMITH, OF NEW YORK, N. Y.

COIN-CONTROLLED VENDING MACHINE.

Application filed November 5, 1925. Serial No. 67,079.

The invention relates to vending or sales machines and relates more particularly to vending machines of the automatic coin controlled cabinet type.

5 An important object of the invention is to provide a coin controlled vending machine of the cabinet type so designed and constructed to permit the selection by the purchaser of the various articles contained 10 within the cabinet by conveniently and manually operative means prior to the actuation of the automatic coin controlled mechanism of the machine.

A further object of the invention is to 15 provide a vending machine of the character described which is effectively locked against pilfery when the door is in open position, thereby permitting one article only to be removed from the machine through the 20 door aperture after the insertion of the required coin.

A further object of the invention is to provide a vending machine of the character described in which latch mechanism is 25 provided for locking the delivery door of the cabinet in open position after a sale has been made, said door being automatically returned to closed position when said latch mechanism is operated; and in which the 30 movement of the door to closed position automatically releases the cabinet to selectively position any desired movable receptacle or compartment within the cabinet in registry with the door aperture.

35 A further object of the invention is to provide a vending machine of the character described in which the operating mechanism is designed to selectively bring into registration with a door aperture articles carried 40 by a container which may be moved vertically or horizontally and from either direction as from right to left and vice versa with a horizontal container or upwardly or downwardly with respect to a vertically moved container.

A further object of the invention is to provide a vending machine in which a minimum of operating parts are required, said machine may be economically manufactured 50 and disposed against a wall to occupy a relatively small area, and which machine is simple in operation and may be conveniently operated by the purchaser, said machine being further of pleasing design, well pro-

portioned in assembly, and ornamental in 55 appearance.

With such objects in view, as well as other advantages which may be incident to the use of the improvements, the invention consists in the parts and combinations thereof 60 hereinafter set forth and claimed, with the understanding that the several necessary elements constituting the same may be varied in proportion and arrangement without departing from the nature and scope of the 65 invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:—

70 Fig. 1 is a front elevation partially broken away, of one preferred embodiment of the invention.

Fig. 2 is a vertical sectional view on line 2—2 of Fig. 1.

Fig. 3 is a horizontal section on line 3—3 of Fig. 1.

Fig. 4 is an enlarged detail view of the latch mechanism for maintaining the door in open position.

Fig. 5 is a similar view showing the means for normally maintaining the door in closed position, and its manner of release by the coin controlled mechanism.

Fig. 6 is a detail view partially in section 80 and showing the manner of alternately obstructing and exposing the coin slot 40.

Referring to the drawings, the embodiment illustrated comprises a vertical cabinet structure 1 consisting of front, side and rear 95 walls suitably joined together as in any preferred cabinet construction. The side walls 2 of the main cabinet are adapted to house for vertical reciprocation therein upon rails or guides 3, a movable article containing element 4 consisting of side walls 4^a and a plurality of intervening transverse preferably inclined shelves or partitions 5, the whole 100 forming a series of receptacles or compartments movable within the cabinet. The 105 receptacles are designed to carry the different varieties of articles to be sold, said articles being preferably arranged one within

each of the compartments formed by the shelves 5 and visible for inspection through the glass or other transparent window 6 provided in the front wall of the cabinet structure. If desired a top compartment 7 may be provided having a transparent front window 8 through which is displayed for public inspection the nature and manufacturing origin of the article contained within the several compartments of the vertically reciprocable element 4. Or if desired the compartment 7 may be utilized as a storage area. In the embodiment illustrated the articles displayed for sale consists of collars 8^a each of which is preferably enclosed within a protective wrapper 8^b of paper or other material. The style and manufacturing origin of the collar may be represented by the sample within the upper compartment 7, and a different size thereof may be contained within each compartment formed by the inclined shelves 5 of the movable container 4. These sizes may be indicated to the purchaser by any suitable means such as cards or tabs affixed to the wrappers 8^b in which the corresponding size collars are contained. The purchaser is thereby enabled to locate the collar which he desires before he proceeds to operate the machine to purchase his collar. It will be understood that instead of collars any desired merchandise may be stored within the machine which is particularly designed to accommodate articles of various sizes or character which may be selected at will by the purchaser. It will be further apparent that the articles may if desired be uniform in character and the nature of the latter or the particular manner of classifying the same does not in any way detract from the improved and advantageous features of the present invention.

The cabinet 1 is or may be further provided with an auxiliary storage cabinet 9 having a hinged door 10 and a series of shelves 11 for conveniently storing a surplus supply of articles contained within the cabinet proper, and to enable the latter to be conveniently replenished after the several compartments have been wholly or partly sold out. The top 12 of the auxiliary cabinet 9 may form a convenient counter to receive the contents of the receptive compartments of the vertically reciprocable container 4 as the same are automatically discharged by gravity from the machine when the latter is actuated by the purchaser.

A door aperture 13 is provided in the front of the cabinet 1 preferably adjacent to the counter 12, said aperture being designed to be normally closed by a movable door or window 14, which latter may be provided with a central panel of glass or other transparent material. In the machine illustrated the door slides vertically. The front wall of the cabinet is suitably cut-away as

illustrated for the reception of the door 14 to permit the same to be opened and closed without interfering with the vertical travel of the article container 4. The container 4 may be formed of wood or thin sheet metal and is preferably of light weight to allow the receptive compartments thereof to be selectively aligned easily in registry with the door opening with a minimum of effort on the part of the purchaser. The rear portion of the cabinet frame is provided with a removable section or door 22 to permit the container 4 to be assembled within or removed from position within the cabinet. It is further possible to restock the compartments of the container 4 without removing the latter from the machine, by the removal of the door or section 22. By providing the plurality of forwardly inclined shelves 5 the machine becomes automatic in its discharge of the articles by gravity, to the counter 12 when the door is opened.

The vertical reciprocable article container 4 is further provided on one side thereof with a longitudinal rack member 15 which extends preferably the full length of the container. A transverse shaft 16 is suitably journaled within the frame 1 at the side of the machine having secured to its inner end a gear or pinion 17 suitably housed within a protective casing 18 and meshing with the teeth of the rack member 15. The shaft 16 has secured thereto at its outer end an operating crank or handle 19 by means of which the pinion 17 may be rotated to vertically reciprocate the container 4 on the tracks or guides 3 in either direction within the cabinet or frame 1 of the machine. The portion of the cabinet frame 1 in which is journaled the shaft 16 may have housed therein a suitable escapement mechanism, friction clutch or brake 21 designed to cooperate with or bear against the shaft 16 to assist in retarding the tendency of the crank 19 to rotate by gravity when the container 4 is being lowered. If desired suitable friction braking means may be provided within the cabinet frame and bearing against the side walls of the container 4 to serve the same purpose in retarding the tendency of the container to slide downwardly by gravity on the tracks or guides 3. A hydraulic brake consisting of a piston and a piston rod operating within a hydraulic cylinder containing any suitable fluid may be employed if desired to retard the tendency of the container to move downwardly by gravity.

Suitably housed within the cabinet frame below the shaft 16 and pivoted as at 23 to said frame is a weighted lever 24 having its weighted end resting or otherwise engaging against the top and extension 25 of the frame of the door 14. When the door is in its normal closed position as illustrated in Figs. 1 and 2 the position of the lever 24

is such that its inner end 26 is depressed and maintained by the door out of engagement with the peripheral teeth of the pinion 17, to permit free rotation of said pinion 5 by the crank or handle 19 to position the desired compartment of the container 4 in registry with the door aperture 13. The door frame 14 is further provided with a depending extension or ear 27 having a pin 10 or projection 28 thereon engaging a slot 29 in one arm of a bell crank lever 30 suitably pivoted as at 31 to the frame of the cabinet, the latter being suitably cut-away or recessed at 32 as illustrated in Fig. 2 to provide a 15 housing for the bell crank lever 30. The lower end of the bell crank lever is provided with a pin or projection 33 engaging a slot or recess 34 in one end of a floating link member 35 housed within the recess 32 in 20 the frame and having its other pivoted as at 36 to a lever 37 secured on the shaft 38 of the coin controlled mechanism. The latter may be of any well known or preferred type which is designed to be operated 25 by means of a handle or crank 39 secured to the outer end of the shaft 38, only when a coin of the proper denomination has been first inserted in the coin slot 40 provided 30 for the purpose in the coin controlled housing 41 secured in any preferred manner to the side of the machine frame. For example any suitable coin control may be utilized, or one such as is fully described in my co-pending application, Serial No. 464,770, 35 filed April 27, 1921, for coin controlled device. An examination of the coin controlled mechanism described in my said co-pending application will aid in a complete understanding of the present machine and 40 said other application is hereby made a part hereof so far as it is necessary to the understanding and operation of the invention herein claimed.

The bell crank lever 30 and link 35 are 45 normally maintained in the position illustrated in Fig. 1 and as illustrated in full lines in Fig. 5 with the door 14 in its upper most or closed position, by means of a coil spring 42 engaging at one end the slot 34 in the link 35, said spring being secured 50 at its other end as at 43 to the frame of the cabinet 1. The door 14 is furthermore normally locked or maintained in its upper most or closed position by means of a lever 55 55 pivoted at 45 to the inner side of the cabinet, said lever having a projection 46 normally maintained in the path of the door frame 14 by means of a coil spring 47 engaging 60 at one end the lever 44 and suitably housed at its other end as at 48 within the side walls of the cabinet frame 1. The pivoted lever 44 is provided at its lower end with a hinged section 49 normally engaging a pin or projection 50 on the floating link 35 65 by means of which the projection 46 of the

lever 44 is moved from the path of the door frame when the link 35 is moved to the right by the actuation of the coin control handle 39, to permit the door to be opened. The initial movement of the link 35 to the right 70 when the crank 39 is moved in a corresponding direction first removes the projection 46 out of the path of the door 14 and the latter is maintained in closed position by the tension of the coil spring 42. Continued movement of the link 35 engages the opposite end of this slot with the pin 33 of the bell crank lever 30. Thereafter the latter is swung on its pivot 31 against the tension of the spring 75 42, resulting in the door 14 being moved downwardly to open position within its guides, due to the engagement of the projection 28 on said door with the elongated slot 29 of the bell crank lever. The described movement to the right of the floating lever 80 35 brings its projection 50 below and to the right of the lower section 49 of the pivoted lever 44. The latter has its projection 46 maintained in sliding engagement against the side of the door frame 14 by the pressure 85 of the spring 47 when the door is moving downwardly to open position.

The tendency of the coil spring 42 is to return the door to its normal uppermost closed position, and to render it unnecessary 90 for the operator to maintain his grasp on the coin control handle 39 after the door has been opened, latch mechanism is provided to automatically secure the door in open position to permit the operator to obtain access 95 to the article within the particular compartment of the container 4 which is in alignment with the door aperture 13, in the event that said article is not immediately discharged by gravity on to the counter 12. 100 This latch mechanism consists in a lever 51 pivoted at 52 to a suitable bracket secured to the frame 1 of the machine, said lever having its upper hooked end 53 pressed by a spring 54 in sliding engagement against the 105 side of the door frame 14. When the door has been moved to lowermost or open position the hooked end of the lever 51 engages the top of the door frame to maintain the door in open position. In order to release 110 the door and permit the same to be again moved to closed position a plunger 55 is provided suitably mounted for horizontal reciprocation within the frame 1 and having its inner end pivoted as at 56 to the lower end 115 of the latch lever 51. When the plunger 55 is pressed inwardly by the operator to release the latch lever 51 from engagement with the door 14 the tension of the coil spring 42 swings the bell crank lever 30 on 120 its pivot 31 to elevate the door to closed position. This movement by the tension of the spring 42 also carries the floating link 35 to the left and its projection is permitted 125 to pass the section 49 of pivoted lever 44 by 130

reason of the loose hinged connection 57. The pressure of coil spring 47 serves to again engage projection 46 of lever 44 with the frame of the door 14 to again lock the latter in closed position.

The manner of operating the described machine is briefly as follows: The prospective purchaser selects by eye the article he desires within one of the compartments of 10 the container 4. Assuming the door to be closed, locking projection 26 of weighted lever 24 is thereby held out of engagement with pinion 17. The purchaser turns the crank handle 19 in the proper direction to 15 register the compartment containing the article desired, in alignment with the door aperture 13. The purchaser then deposits the proper coin in the slot 40 of the coin control housing 41, permitting crank handle 20 39 to be rotated or swung to the right. This movement through the medium of the various links and levers described permits the door to be lowered to open position where it is temporarily locked by the latch lever 51 25 and an article is discharged by gravity to the counter 12. Should the article become jammed within its compartment the purchaser is enabled to reach through the door aperture to dislodge his purchase. Assuming 30 that the machine is left in this condition with the door in open position, the handle 19 can not be further rotated to bring a filled compartment into registry with the aperture 13, due to the locking engagement 35 of projection 26 with pinion 17 occurring in the manner described as soon as the door has been opened. It will be further understood that the locking lever 24 is suitably housed within a protective casing to prevent 40 the same from being disengaged from the pinion 17 through the open door by an unauthorized or unscrupulous person. A succeeding purchaser who is desirous of obtaining a succeeding article in one of the remaining filled compartments of the machine, 45 first depresses the plunger 55 resulting in the door being automatically moved by the spring 42 to closed position and by the same movement the coin control handle 39 is also 50 moved to its normal position rendering the coin slot 40 unobstructed. The described automatic movement of the door to closed position releases the locking lever 24 from engagement with the pinion 17 and the 55 succeeding purchaser is thereby enabled to rotate the crank 19 to bring the selected article into engagement with the door opening. He then inserts his coin in the slot 40 and again operates the machine in the manner heretofore described.

Referring to Fig. 6 means are shown for obstructing the coin slot 40 to prevent the insertion of a coin until the mechanism has been returned to normal position by the 60 manipulation of the plunger 55. A sliding

shutter 57 is carried by suitable guides within the housing 41 and is provided with a depending ear having a projection 58 thereon. Said projection engages an elongated recess 59 of the lever 37 secured to the coin 70 control shaft 38. When the handle 39 is swung to the right as illustrated in Fig. 6 to latch the door in open position the shutter 57 is moved by the lever 37 into position to obstruct the coin slot 40. When the 75 mechanism is returned to normal position it will be apparent that the shutter 57 is carried by arm 37 to the left and out of registry with the coin slot, thereby permitting a subsequent purchase to be made.

What I claim is:

1. In a coin controlled vending machine the combination of a cabinet having a door aperture and a door normally closing the same, a container having article receiving 85 pockets, mounted for vertical reciprocation within said cabinet, means for vertically reciprocating said container to selectively align said compartments with said door aperture, means for moving said door to 90 open position to discharge the contents of a selected compartment, and means controlled by said door for locking said container against movement while said door is in open position.

2. In a coin controlled vending machine the combination of a housing having a door aperture and a door normally closing the same, a container having a plurality of article receiving pockets mounted for vertical reciprocation within said housing, means for reciprocating said container within said housing to selectively align said compartments with said door aperture, means normally locking said door in closed position, 100 means cooperating with said door locking means and adapted to move said door to open position to discharge the contents of a selected compartment, and means for locking the container against movement while said door is open.

3. In a coin controlled vending machine the combination of a cabinet having a door aperture and a door normally closing the same, a container having a plurality of article receiving compartments therein mounted for vertical reciprocation within said cabinet, manually controlled means for imparting movement to said container relative to said cabinet to selectively position a desired 115 compartment in alignment with said door aperture, locking means normally held out of engagement with said container, and means for moving said door to open position to discharge the contents of said aligned 120 compartment, said movement of said door to open position actuating said locking means to hold said container against movement while said door is open.

4. In a coin controlled vending machine 130

- the combination of a housing having a door aperture and a door normally closing the same, a container having article receiving pockets, mounted for vertical reciprocation within said cabinet, means for vertically reciprocating said container to selectively align said compartments with said door aperture, means for moving said door to open position to discharge the contents of a selected compartment, means controlled by said door for locking said container against movement while said door is open, and means controlled by said door-moving means for automatically moving said door to closed position after the contents of a single compartment have been discharged from the machine.
5. In a coin controlled vending machine the combination of a cabinet having a door aperture and a door normally closing the same, a container having a plurality of article receiving pockets mounted for vertical reciprocation within said cabinet, means for vertically reciprocating said container within said cabinet to selectively align said compartments with said door aperture, means normally locking said door in closed position, means adapted to release said door locking means to permit said door to be moved to open position to discharge the contents of a selected compartment, means controlled by said door for locking the container against movement while said door is open, means for holding said door in open position, and means cooperating with said releasing means and said locking means for returning said door to closed position after said door holding means have been released.
6. In a coin controlled vending machine the combination of a housing having a door aperture and a door normally closing the same, a container having a plurality of article receiving compartments mounted for vertical reciprocation within said housing, means for vertically reciprocating said container relative to said housing to selectively position one of said compartments in registry with said door aperture, means for moving said door to open position to discharge the contents of a selected compartment through said door aperture, means for locking said container against movement while said door is open, means actuated by said door-moving means for preventing movement of the latter while said door is open, and means cooperating with said door-moving means and said actuated means for returning said door to closed position.
7. In a coin controlled vending machine the combination of a cabinet having a door aperture and a door normally closing the same, a container having a plurality of article receiving compartments mounted for vertical reciprocation within said cabinet, means for vertically reciprocating said container to selectively position one of said compartments in registry with said door aperture, means for moving said door to open position to discharge the contents of a selected compartment through said door aperture, means controlled by said door for locking said container against movement while said door is open, latch mechanism for maintaining said door in open position, and means cooperating with said door-moving means and said shutter for returning said door to closed position, said movement of the door to closed position automatically releasing said container locking means to permit free movement of said container relative to said cabinet when said door is closed.
8. The combination of an enclosing cabinet, a series of vending receptacles reciprocable therein, means for reciprocating said receptacles, a door in said cabinet relative to which any receptacle may be positioned to make its contents accessible therethrough, means controlled by the door for locking said receptacles against movement when the door is open, means for opening the door, and means holding the door opening means from operation.
9. The combination of an enclosing cabinet, a series of vending receptacles vertically reciprocable therein, said receptacles having a plurality of inclined partition members forming spaced compartments, a door in said cabinet relative to which any receptacle may be positioned to render the contents of a desired compartment accessible therethrough, means controlled by the door for locking said receptacles against movement when the door is open, means normally holding said door in closed position, and means actuated by said door-holding means for opening said door to discharge the contents of a selected compartment by gravity through said opened door.
10. The combination of an enclosing cabinet, a series of vending receptacles vertically reciprocable therein, said receptacles having a plurality of inclined partition members forming spaced compartments, a door in said cabinet relative to which any receptacle may be positioned to render the contents of a desired compartment accessible therethrough, means for locking said receptacles against movement when the door is opened, means normally holding said door in closed position, and means actuated by said door-holding means for opening said door to discharge the contents of a selected compartment by gravity through said opened door.

In testimony whereof I affix my signature.
GOODWIN B. SMITH.
